ATTORNEY.

UNITED STATES PATENT OFFICE.

FREDERICK W. HORSTMANN, OF MAPLEWOOD, NEW JERSEY.

FUR-SHEARING MACHINE.

Application filed June 22, 1925. Serial No. 38,832.

This invention relates to fur-shearing machines and more particularly to a novel and improved device adapted for cutting or shearing fur extremely close and also uniformly as the skin is advanced or drawn by the cutting mechanism.

Various types of mechanisms, more or less complicated, have been employed for presenting skins bearing fur of non-uniform depth to shearing mechanism for the purpose of obtaining skins having a uniformly deep coat of fur thereon. In addition, these machines are designed to secure a fairly close cut of the fur.

In one of the most commonly utilized machines employed for the above purposes, a plurality of rotary shearing knives operate in close proximity to a bed knife. In such machines it has been the practice to employ a relatively large diameter roller or other curved bar for presenting the fur to the cutting knives. In conjunction with the shearing knives a suction device is employed. The function of the suction device is to remove the sheared fur from the mechanism, although with certain kinds of skins the suction device also assists in bringing the fur in proper position for shearing. These machines have not proven entirely satisfactory for the reason it is not possible to properly present the fur to the cutting devices so as to obtain an extremely close cut. The reason why this result is not obtainable may be attributed to the relatively large curved

surface of the apron or stretcher bar. Such surface does not permit one to bring the skins closely enough to the cutters to secure a close cut because there is insufficient clearance between the roller and the knives. Furthermore, with a large curved surface it is not

possible to present the fur instantly and quickly to the cutting mechanism since the fur which extends at right angles to the surface of the skin must necessarily assume various angular relations with respect to the cutters as the skin is drawn over the stretcher bar.

Another object of my invention is to provide a fur shearing machine which may be operated to produce a very close cut of the fur which is of uniform depth throughout.

A further object of my invention is to provide a machine for trimming fur which will develop, through extremely close and uniform cutting of the fur, the peculiar desirable characteristics which may be inherent therein.

Other objects of the invention will be apparent as the description is read.

In order to more fully understand and appreciate my invention reference may be had to the accompanying drawings showing the preferred embodiment thereof, wherein

Figure 1 is an end view, partly in section, showing the rotary cutters in their relation to the bed knife.

Figure 2 is a front view.

showing the relation of the stretcher bar or apron to the knife edge, the bed knife and rotary knives.

Referring now to the drawings, 5 designates generally the conventional type of frame or stand on which may be mounted a motor 6 for driving the rotary knives 7, said knives being mounted on the horizontal shaft 8 and operable by means of an endless belt 9. The rotary knives are enclosed within a housing or casing and protected by a hinged cover or guard 10, there being a rear opening 11 for connection to an exhaust fan or blower, not shown. A bracket 12 supported on the stand or frame and secured thereto by suitable bolts has attached thereto an angularly disposed, upwardly extending, bed knife 13. The bed knife may be adjusted to different degrees with relation to the rotary knives 7, this portion of the machine or mechanism being old and well-known in the art.

My invention proper consists in mounting a pivoted frame to the front of the stand or support and comprises a horizontal shaft 14, supported in suitable bearings 15 at the front of the frame. On the said shaft, I provide a pair of vertical, parallel members 16, 17, to which are connected, preferably at right angles thereto, a buffer 18 secured to the members 16, 17, by the angular brace bars 20. An adjusting screw 21 attached to the front of the frame limits the inward movement of the members 16, 17, and the buffer 18 in one direction and a pair of bars 22 attached to the frame at one end and slotted as indicated by numeral 23, are suitably connected to the members 16, 17, so as to limit the movement thereof outwardly or in the opposite direction.

Adjustably connected to the upper ends of the members 16, 17, are a pair of angularly bent arms 24, which are slotted as at 25 to permit of the vertical adjustment thereof. The arms 24 carry and support a horizontal, flat, stretcher bar or apron 26 to which the skin or fur is held or drawn as the said skin is presented to the cutting action of the knives. Referring in particular to Figure 3, it will be observed that the inner, front edge 27 of the bar or apron is provided with an attenuated knife edge, presenting a small or restricted cross sectional surface through which the skin may pass so that the hairs drawn in between the bed knife 13 and the rotary knives 7 may be properly presented to the shearing action of the said knives and thus produce an even, regular cut. It will be readily appreciated

that if a roller were used instead of the bar 60 or apron at this point, that certain of the hairs of the fur skins would lie tangential to such roller and consequently, as the skin is pulled or drawn thereover, the same cutting action could not be effected as in the 65 manner shown. By using a flat bar or apron of this type, I am enabled to adjust the cutting action to produce very close, regular and even work and obtain finer adjustments of the flat bar relative to the 70 cutting edges of the knives when they wear. The slotted ends of the arms 24 permit of the vertical adjustment of the stretcher bar or apron 26 whereas the set screws 21 limit the inward position of the stretcher bar or 75 apron relative to bed knife and the rotary knives as shown by Figure 1 of the drawings.

In actual operation, when the frame, consisting of the members 16, 17, is held in its 80 extreme outer position by the guides 22, the fur or skin is positioned over the edge of the stretcher bar or apron. As the buffer 18 is engaged by the person, the stretcher bar or apron, carrying the skin is advanced 85 toward the knives and as the fur or skin is drawn over the edge 27 of the stretcher bar or apron, the hair of the furs is cut evenly and regularly, producing the desired 90 even work.

While I have illustrated and described my invention with some degree of particularity, I realize that in practice various alterations therein may be made. I therefore reserve the right and privilege of changing 95 the form of the details of construction or otherwise altering the arrangement of the correlated parts without departing from the spirit of the invention or the scope of the appended claim.

Having thus described my invention, what I claim as new and desire to secure by United States Letters Patent is:—

In a fur trimming machine, the combination with a stand having a bed knife and rotary knives cooperating therewith, a frame pivotally mounted on said stand, arms carried at the upper end of said frame, a flat stretcher bar or apron formed with said arms, means for moving said stretcher bar in an approximately horizontal plane toward the rotary knives and in proximity to the bed knife and means for limiting the inner and outer movements of said frame and stretcher bar.

In testimony whereof I affix my signature.

FREDERICK W. HORSTMANN. [L. S.]
